UNITED STATES PATENT OFFICE.

BRADLEY WOODHULL, OF DUNMORE, PENNSYLVANIA, ASSIGNOR TO THE SCRANTON STOVE WORKS, OF SCRANTON, PENNSYLVANIA.

DESIGN FOR A SHELF-SECTION FOR STOVES OR RANGES.

SPECIFICATION forming part of Design No. 28,599, dated May 10, 1898.

Application filed February 25, 1898. Serial No. 671,700. Term of patent 14 years.

To all whom it may concern:

Be it known that I, BRADLEY WOODHULL, a citizen of the United States, residing at Dunmore, in the county of Lackawanna and State 5 of Pennsylvania, have invented and produced a new and original Design for a Shelf-Section for Stoves or Ranges, of which the following is a specification, reference being had to the accompanying drawings.

10 In the drawings, Figure 1 is a perspective view of a shelf-section bearing my design. Fig. 2 is a top plan view of the shelf proper.

The leading feature of the design consists 15 in the shape and configuration of the shelf- section as a whole and the separate parts thereof, as herein described and claimed.

The letter A represents the shelf proper, the top of which is ornamented in open scroll and leaf design, the edge of the shelf being 20 serpentine in form, as shown, and ornamented with a scroll and leaf design, the lower edge following and finishing with the outline of ornament. Below the shelf the smoke-pipe section bears the open scroll and leaf ornament B, being a part or continuation of the scroll and leaf design C on the pipe-section and made to contrast therewith, the design C appearing through the open-work of the design B. On each side of the pipe-front are 25 the open scroll and leaf design brackets B', and resting on the back edge of the shelf is the top strip D of open scroll and leaf design.

E is the back rail, resting on the range-top, bearing a central band of scroll and leaf ornamentation E' and the beaded border e at the top and bottom thereof. 35

F are cup-shelves located at right and left ends of said back strip, having open carved tops and solid carved edges. 40

Having thus fully described my invention, what I claim as new, and desire to secure by Letters Patent, is—

1. In a design for shelf-section of stove, the design for the shelf E, substantially as shown 45 and described.

2. In a design for shelf-section of stove, the design for the smoke-pipe section, substantially as shown and described.

3. In a design for shelf-section of stove, the 50 design for the side brackets, substantially as shown and described.

4. In a design for shelf-section of stove, the design for the back rail, substantially as shown and described. 55

5. In a design for shelf-section of stove, the design for the top strip, substantially as shown and described.

6. The design for shelf-section of stove; substantially as herein shown and described.

BRADLEY WOODHULL.
